UNITED STATES PATENT OFFICE

2,673,668

ADJUSTABLE GARMENT HANGER

William P. Riddell, London, Ontario, Canada

Application August 30, 1950, Serial No. 182,197

1 Claim. (Cl. 223—89)

1 This invention relates generally to a coat hanger, and relates more particularly to a coat hanger having arms that can be extended endwise thereof to accommodate the shoulders of coats having varied widths.

Adjustable coat hangers of the particular type with which this invention is concerned have been provided in the past. The general construction of the means for securing adjustment has been more or less complex either in manufacture or in use or both, so that the proposals of the past have not been generally accepted. I have devised an adjustable coat hanger having a simple, practical construction which I feel is a substantial improvement over the teachings of the prior art.

My coat hanger has a body portion with two arms slidably mounted therein for extension endwise thereof to accommodate coats or other garments having shoulders of various widths. According to the invention I provide a locking means for locking engagement with each of the slidably mounted arms, and spring means mounted on the hanger body loaded to urge the locking means into operative engagement with the arms whereby to maintain them in any given position of adjustment. The invention will be clearly understood after reference to the following detailed specification read in conjunction with the drawings.

In the drawings:

Figure 1 is a view showing a coat hanger of the present invention with the extendable arms in a completely retracted position.

Figure 2 is a view of the same coat hanger showing the arms in an extended position.

Figure 3 is a perspective view showing one of the arms.

Figure 4 is a sectional view along the line 4—4 of Figure 1.

Referring to the drawings, the coat hanger there shown has a body portion generally indicated by the numeral 10 that is formed, in the usual way, with two diverging downwardly sloping edges 11 and 12 over which the shoulders of a coat or other garment can be hung. The body portion 10 in addition has slideways 13 and 14 each to slidably receive therein one of the arms 16 and 17. In the embodiment of the invention shown the two slideways 13 and 14 communicate with each other. It will be understood of course, that they need not do so.

In use, the free ends of the arms 16 and 17 are extended from the ends of the body to engage and support the inner tip of the shoulders of the

garment. They are formed with enlarged free ends as shown to support the padded shoulder of a garment and co-act with the sloping edges 11 and 12 to support the garment.

5 As indicated above, a coat hanger that is generally capable of adjustment in this way is not new. My invention is the provision of a simple and practical means for controlling the locking means that retains the slideable arms 16 and 17 in a predetermined position of adjustment. According to my invention, each arm 16 and 17 has a locking means, and a spring means carried by the body of the hanger loaded to urge the locking means into operative locking engagement with the arms.

In the embodiment of the invention shown, the locking means comprises a pin 18 which enters through a hole 19 in the body 10 to bind against the arm 16. A spring 20 rigidly secured to the hanger body as at 21 is loaded to urge the pin 18 into operative engagement with the arm 16. The hole 19 must of course be wide enough to permit some longitudinal movement of the pin 18 therein without binding.

20 The arm 16 is also formed with a series of longitudinally spaced apart recesses 18a for co-action with the pin 18 as illustrated in Figure 4. It should be noted that the pin 18 extends at substantially right angles to the free end of the loaded leaf spring so that its longitudinal axis is inclined to the longitudinal axis of the arm 16.

The inclination is such that the rounded free end of the pin will ride out of the recesses 18a as the arm 16 is slid from the body of the hanger 35 but will bind in the recesses 18a to resist any forces that tend to insert the arm in the body of the hanger. In order to slide the arm from an extended position into its slideway it is necessary to manually withdraw the pin clear of the recesses 18a.

30 Other arrangements of pin 18 and arm 16 that will cause the arm to bind against forces tending to slide it into the body of the hanger but will permit it to be withdrawn from the body of the hanger will be apparent to those skilled in the art after consideration of my method.

40 For convenience, I have described in detail only the locking of the arm 16, but it will be understood that the locking of arm 17 is identical with the locking of arm 16.

A wire 22 for the purpose of hanging a pair of trousers or the like can be simply incorporated into a hanger according to my invention.

The embodiments of my invention other than 55 the ones shown will be apparent to those skilled

in the art and I do not intend that my patent should be limited to the specific embodiment there shown.

What I claim as my invention is:

In a garment hanger having a body with two diverging downwardly sloping edges over which the shoulders of a coat can be hung, two arms, said body being formed with two slideways each to slidably receive one of said arms and to dispose one of said arms with its free end extending from one end of said body and the other of said arms with its free end extending from the other end of said body, whereby said arms co-act with said shoulder supporting edges to support the shoulders of a garment, two leaf springs each secured at one end to said body, one of said springs having its longitudinal axis aligned with the longitudinal axis of one of said slideways, the other of said springs having its longitudinal axis aligned with the longitudinal axis of the other of said 20 slideways, a locking pin carried by each of said springs adjacent its free end, said body being formed with holes communicating with said slideways whereby each of said pins carried by said leaf springs enters into one of said slideways, said 25

arms being formed with longitudinal spaced apart notches to receive said pins, said springs being loaded to normally force said locking pins into their respective slideways, and into engagement with said notches in said arms, said pins extending from said leaf springs to enter said notches at an incline to permit said arms to be freely drawn in an outward direction from said body but to positively lock them from being slid into said body unless said locking pins are withdrawn from engagement with said arms.

WM. P. RIDDELL.
